UNITED STATES PATENT OFFICE

2,428,342

FOOT CORRECTIVE APPLIANCE

Bernard H. Sherman, Boston, Mass., assignor of
one-third to Edwin M. Warwick, Walpole, and
one-sixth to Harold E. Cole, Taunton, Mass.

Application December 1, 1944, Serial No. 566,059

12 Claims. (Cl. 36—71)

1

This invention relates to a foot correcting appliance.

One object of my invention is to provide an appliance that will treat a weak or deformed foot and obtain both a palliative and curative result. Another object is to provide a combination of a fore portion and a heel portion connected together which serves to correct deformities or weakness, or both, in the fore and heel portions of the foot simultaneously. Since both portions of the foot are coordinated in function and can best be corrected together this linking together of said two portions affords a distinct advantage.

A further object is to provide means whereby my appliance is made adjustable so that it may be adapted to fit the individual foot.

My appliance will counteract abduction of the forefoot with relation to the rearfoot in a state of weakfoot. Thus without directly supporting the long arch from below the bones of the foot are compelled to resume their normal relationship and while so retained a muscular and ligamentous strengthening takes place until the foot functions naturally without this artificial aid. Thus by providing an appliance that does not apply direct pressure the weakened soft structures are free to shorten themselves and will become strong enough to perform their function of keeping the long arch in place unassisted.

The foregoing and other objects which will appear as the nature of the invention is better understood, may be accomplished by a construction, combination and arrangement of parts such as is disclosed by the drawings and specification. The nature of the invention is such as to render it susceptible to various changes and modifications, and, therefore, I am not to be limited to said disclosure; but am entitled to all such changes therefrom as fall within the scope of my claims.

In the drawings:

Figure 1 is a plan view of my appliance for a right foot.

Figure 2 is a bottom view thereof.

Figure 3 is an outer side elevational view of said appliance.

Figure 4 is a sectional view taken on the line 4—4 of Figure 1.

Figure 5 is a sectional view taken on the line 5—5 of Figure 1.

Figure 6 is a plan view of the inner side part of the heel portion of my appliance.

Figure 7 is a plan view of the connector that links the heel and forefoot portions of my device.

2

Figure 8 is a perspective view of my appliance in position of use on a right foot.

Figure 9 is a plan view of my appliance, similar to Figure 1; but with the upstanding part of the forefoot inner side piece removed.

As illustrated, I show an appliance that is adapted to fit the right foot of a person. Said appliances are commonly used in pairs for both right and left feet. In referring to the outer side 10 of any part of my appliance I mean the side that is intended for the outer side of the foot, which is the right side of a right foot. Likewise in referring to the inner side I mean the side intended for the inner side of the foot which is the left side of the right foot.

My appliance consists of three main parts, namely, a heel member or portion H, a forefoot member or portion F and a connecting member C that connects H and F. These three portions could be made in one piece or in fewer pieces than shown; but they would not have the same facility in use or be as freely adjustable. Said heel portion H forms a cradle in which the heel can rest. It preferably is made of a rear outer part 11, a front outer part 12, a rear inner part 13 and a front inner part 14.

The inner surfaces are concaved-shaped. Said front outer part 12 has an outwardly extending flange 12a at the top which overhangs the top edge of the adjoining part 11 as shown in Figure 3 of the drawings whereby said front and rear parts 11 and 12 are adjustably associated together. This likewise is true of the inner rear part 13 and inner front part 14 since the latter has an outwardly extending flange 14a. Said flanges 11a and 14a serve to hold said front and rear parts steady when set in a predetermined position.

Said rear parts 11 and 13 each have a slot 16 and said front parts 12 and 14 each have a screw-threaded hole 18 therein. Screws 20 of the Allen type having a hole in their outer end extend through said slots 16 and screw-threadedly engage said holes 18 and hold the said rear and front parts in engagement with each other. To change the length of said heel portion H said screws 20 are readily loosened and said rear parts 11 and 13 are moved forward or backward to the extent desired and allowed by the length of said slots 16. Thus the forefoot portion F is moved forwardly or rearwardly as said heel portion H is lengthened or shortened.

Said heel outer front part 12 has a lateral extension 22 made integral therewith having an upper cross-serrated surface 22a which has a long slot 23 therein that extends laterally of my ap-

pliance. Said heel inner front part 13 has a lateral extension 24 at the front which has a screw-threaded hole 25 therein that is adapted to aline with said slot 23 when said front parts 12 and 14 are in normal position relative to each other. Its under surface is cross-serrated as at 24a. A screw 26 holds said front parts 12 and 14 together, by extending through said slot 23 into said hole 25 after said right front part 12 has been adjustably positioned laterally relative to said left front part 14.

Said inner front part 14 of said heel portion H has a front extension 27 having a hole 28 therein. An upper surface portion of said extension 27 is preferably radially serrated as at 30 on its upper surface.

This heel member H could be used alone in cases where the forefoot portion F is unnecessary. Its main function, however, is to provide a secure anchor by which said forefoot portion is enabled to retain its predetermined position.

Said forefoot member F consists of an outer side 31 cross-serrated on its upper surface as at 31a, and an inner side 32 cross-serrated on its under surface, as at 32a, the teeth of which mesh with serrations 31a. Said outer side 31 has an integral lateral extension piece 33 which has a slot 34 therein extending towards said inner side 32 which latter has a lateral extension 35 having screw-threaded hole 36 therein. A set screw 37 is adapted to enter said slot 34 and engage the threads of said hole 36, thereby holding the two sides together. Channel portions 38 are formed in said inner side piece 32 at its forward and rearward extremities, which extend to the inner lateral edges of said side 29, in which channels 38 said extension piece 33 slidably fits. Said forefoot inner side 32 has a radially serrated under surface 39 at its rear portion and a screw-threaded hole 40 extends therethrough.

Said heel member H is connected to said forefoot member F by a link or connector C which extends between heel member H and forefoot member F. This connector C has a radially serrated under surface 41 at its rear end whose teeth are adapted to grip with the teeth of said radially-serrated surface 30 on said heel inner front part 14 to thereby prevent rotative movement between said connector C and said heel portion once their relative position is determined. A screw-threaded hole 42 in said connector C at the center of said serrated surface 41 is adapted to aline with said hole 28 in said heel part extension 27 when in normal position of use, and a set screw 43 extends through said hole 28 and engages the threads of said hole 42.

At the front end of said connector C there is a radially-serrated surface 46 at its upper surface in the center of which is a hole 47 through which a screw 48 extends and engages the thread of hole 40. Said screws 43 and 48 permit variations in the angle of said connector C in its position between said heel and forefoot portions H and thus the position of said forefoot member F relative to said heel member H may thereby be varied. The teeth of said radially-serrated surface 46 mesh with the teeth of said serrated surface 39.

The anterior border 50 of said forefoot portion outer side 31 at its farthest point forward reaches to a point immediately behind the head of the fifth metatarsal bone when correctly positioned. Thus said outer side 31 exerts pressure first upon the shaft and base of the fifth metatarsal bone and also first upon a part of

the cuboid bone, consequently pressure is exerted in a medial direction upon all the structures in the forefoot which by its continuous pressure tends to effect a cure. As a result of this medial pressure the medial longitudinal arch is raised to its normal position and is retained in this normal position for the period necessary to effect the natural strengthening of the ligaments and muscles concerned. Since these muscles and ligaments are not directly supported from below and since the plantar structures of the foot are not stretched as they would be with a conventional arch support, the above named structures, in conformance with physiological laws will spontaneously become strong enough to support the medial longitudinal arch without assistance.

My foot correcting appliance is intended to be used with the ordinary shoe or other footwear, and by adjusting it to fit the individual foot it is so comfortable that it can be worn throughout the day.

What I claim is:

1. A foot corrective appliance comprising a heel portion, a forefoot portion spaced therefrom, a connector member connecting said portions and bridging said space, and means to adjust the position of said connector, said forefoot portion having an upstanding portion of rigid material at its outer side.

2. A foot corrective appliance comprising a heel supporting member embodying a plurality of sections on each side thereof, two of said sections at opposite sides each having a slot therein extending in a front to rear direction, two other said sections each having an opening therein and when in position of use being adapted to overlie said first sections whereby said slots and openings will be in alinement, and means adapted to enter said slots and openings to hold said sections together.

3. A foot corrective appliance comprising a heel supporting member embodying a plurality of sections on each side thereof connected together lengthwise and crosswise, said sections on the same side being so positioned that they can be moved forwardly or rearwardly relative to each other, the said sections on opposite sides being so positioned that they can be moved laterally relative to each other, movable means adapted to adjustably hold said sections on the same side together and movable means adapted to adjustably hold said laterally movable sections together.

4. A foot corrective appliance comprising a heel supporting member embodying a plurality of sections on each side thereof, two said sections at opposite sides each having a slot therein extending in a front to rear direction, two other said sections each having an opening therein and when in position of use being adapted to overlap said first section whereby said slots and opening will be in alinement, and means adapted to enter said slots and openings to hold said sections together, one said section having a lateral extension portion having a slot therein, another said section opposite said latter section having an opening therein adapted to aline with said latter slot and means adapted to enter said latter slot and opening to hold said latter sections together.

5. A foot appliance comprising a heel portion embodying a plurality of sections at each side thereof, movable means holding said sections together adapted to permit longitudinal adjustment of said sections, movable means holding said sections together adapted to permit lateral adjust-

ment of said sections which are at opposite sides, a forefoot portion embodying two sections, movable means adapted to hold together and permit lateral adjustment of said forefoot sections; a connector member connecting said heel portion and forefoot portion, movable means connecting said connector member to said heel portion, and means connecting said forefoot portion to said connector member.

6. A foot appliance comprising a heel portion embodying a plurality of sections at each side thereof, having openings therein, movable means adapted to enter said openings and hold said sections together to permit longitudinal adjustment of said sections, two opposite said sections having openings therein, movable means adapted to enter said latter sections and hold said sections together to permit lateral adjustment of said sections, a forefoot portion embodying two sections, movable means adapted to permit lateral adjustment of said sections, a connector member connecting said heel portion and forefoot portion together, movable means connecting said connector member to said heel portion, and means connecting said forefoot portion to said connector member.

7. A foot appliance comprising a heel portion embodying a plurality of sections at each side thereof, movable means holding said sections together adapted to permit longitudinal adjustment of said sections, movable means holding said sections together adapted to permit lateral adjustment of said sections which are at opposite sides, a forefoot portion embodying two laterally opposite sections each having upstanding side portions, movable means adapted to permit lateral adjustment of said latter sections, a connector member connecting said heel portion and forefoot portion, movable means connecting said connector member to said heel portion, and means connecting said forefoot portion to said connector member.

8. A foot appliance comprising a heel portion embodying two sections at each side thereof, one said side section on each side thereof having a slot therein and one said side section on each side thereof having an opening therein, both pairs of said side sections overlying each other so that said slots and openings are in alinement with each other, pin members extending into said slots and openings and adapted to hold said sections together, a said side section having a slot therein and another side section laterally opposite thereto having an opening therein, said latter side sections overlying each other so that said latter slot and opening are in alinement, a pin member extending into said latter slot and opening to hold said side sections together, a forefoot portion embodying two sections one said section having a slot therein and the other an opening, said forefoot portion sections overlying each other so that said slot and opening are in alinement with each other, a pin member extending into said slot and opening and adapted to hold said sections together, a connector member connecting said heel portion and forefoot portion having two openings therein, said heel portion and said forefoot portion each having another opening therein which are adapted to aline with said openings in said connector member, and pin members extending into connector member openings and said forefoot portion and heel portion latter-mentioned openings to connect said connector member and said forefoot and heel portions together.

9. A foot appliance comprising a heel portion

embodying two sections at each side thereof, one said side section on each side thereof having a slot therein and one said side section on each side thereof having an opening therein, both pairs of said side sections overlying each other so that said slots and openings are in alinement with each other, adjustable pin members extending into said slots and openings and adapted to hold said sections together; a lateral portion of said side section having a slot therein and a lateral portion of another side section laterally opposite thereto having an opening therein, said latter side sections overlying each other laterally so that said latter slot and opening are in alinement, an adjustable pin member extending into said latter slot and opening to hold said side sections together, a forefoot portion embodying two sections one said section having a slot therein and the other an opening, said forefoot portion sections overlying each other so that said slot and opening are in alinement with each other, an adjustable pin member extending into said slot and opening and adapted to hold said sections together, a connector member connecting said heel portion and forefoot portion having two openings therein, said heel portion and said forefoot portion each having another opening therein which are adapted to aline with said openings in said connector member, and pin members extending into connector member openings and said forefoot portion and heel portion latter-mentioned openings to connect said connector member and said forefoot and heel portions together.

10. A foot appliance comprising a heel portion embodying two sections at each side thereof, one said side section on each side thereof having a slot therein and one said side section on each side thereof having an opening therein, both pairs of said side sections overlying each other so that said slots and openings are in alinement with each other, adjustable pin members extending into said slots and openings and adapted to hold said sections together, a said side section having a slot therein and another side section laterally opposite thereto having an opening therein, said latter side sections overlying each other laterally so that said latter slot and opening are in alinement, an adjustable pin member extending into said latter slot and opening to hold said side sections together, a forefoot portion embodying two sections one said section having a slot therein and the other an opening, said forefoot portion sections overlying each other so that said slot and opening are in alinement with each other, an adjustable pin member extending into said slot and opening and adapted to hold said sections together, a connector member extending diagonally between and connecting said heel portion and forefoot portion having two openings therein, said heel portion and said forefoot portion each having another opening therein which are adapted to aline with said openings in said connector member, and pin members extending into connector member openings and said forefoot portion and heel portion latter-mentioned openings to connect said connector member and said forefoot and heel portions together, said forefoot portion having an upstanding outer side member.

11. A foot corrective appliance comprising a heel portion, a forefoot portion spaced therefrom, a connector member connecting said portions and bridging said space, and means to adjust the position of said connector, said forefoot portion having upstanding portions of rigid material at its inner and outer sides.

12. A foot corrective appliance comprising a heel portion, a forefoot portion spaced therefrom, a connector member connecting said portions and bridging said space, and means to adjust the position of said connector embodying two adjustable fastening members at opposite ends of said connector member in cooperative engagement with said heel portion and forefoot portions, said forefoot portion having an upstanding portion of rigid material at its outer side.
